UNITED STATES PATENT OFFICE.

DONALD B. BECKER, OF WATERVLIET, NEW YORK, ASSIGNOR TO GEO. P. IDE & CO., OF TROY, NEW YORK.

SOFT TURN-DOWN COLLAR.

1,276,479.

Specification of Letters Patent.

Patented Aug. 20, 1918.

Application filed May 18, 1917. Serial No. 168,981.

To all whom it may concern:

Be it known that I, DONALD B. BECKER, a citizen of the United States, residing at Watervliet, in the county of Albany and State of New York, have invented certain new and useful Improvements in Soft Turn-Down Collars, of which the following is a specification.

One of the objects of my invention is to produce a soft turn down collar free from permanent attached buttons.

Sewed on buttons, and other like permanently secured devices for collars are very objectionable inasmuch as they are very likely to come off at any time and serious discomfiture result; besides which such permanently secured fasteners are liable to break off in the laundry and are objectionable in the process of ironing. Therefore it is one of the objects of my invention to remedy this evil by eliminating the sewed on button or other permanently secured clasp, clamp and the like.

Another object of my invention is to provide an additional button hole at each end of the neck band.

Another object of my invention is to provide a soft collar having a neck band and a folded over top portion, the neck band having two button holes at each end in horizontal alinement, near the bottom edge thereof, also a button hole at each end near the upper edge thereof, one of said upper button holes being concealed by the top portion when in folded position, the top fold of the collar being provided with a button hole at each end near the lower marginal edge thereof and adapted to register, when the top portion is in folded position, with one of the two button holes at each end of the neck band.

A further object of my invention is to provide a neck band for a collar of the character described having one end thereof gradually, but materially, reduced in width.

In the drawings:

Figure 1 is a perspective view of a collar embodying my invention.

Fig. 2 is a similar view with the top flap broken away at the inner end.

Fig. 3 is a detail sectional view on the line 3—3 Fig. 1.

Fig. 4 is a detail sectional view on the line 4—4 Fig. 1.

Fig. 5 is a plan view of my improved collar laid out flat before the same is folded, looking at the outer face of the neck band.

Fig. 6 is a similar view looking at the face of the top folded over portion and the inner face of the neck band.

1 represents the folded over top portion which is provided with button holes 2 located at each end and near the bottom marginal edge of the same.

The neck band 3 is provided with the usual button holes 4, 5 at each end thereof positioned near the lower marginal edge of the band; 6 being the usual central button hole of the collar. The neck band is also provided at the long end with the usual button hole 7 and at the shorter end with a button hole 8, the said button hole 8 being in such position on the neck band that it is covered or concealed by the outer top fold when said fold is in its folded position.

In addition to the usual button holes of a collar I provide the neck band with button holes 9 and 10 located near the lower marginal edge of the neck band and substantially in horizontal alinement with the usual button holes 4 and 5 when the collar is folded in position to be worn. A detachable button is secured in the button holes 9 and 10 and projects through the button holes 2 of the outer fold of the collar, whereby the outer fold and the neck band are secured together near their front edges. A detachable button is secured in the button hole 8 and is adapted to be engaged by the button hole 7 on the long end of the collar whereby the ends of the collar are permanently secured together at the top edge of the collar, the lower edges of the collar being secured together by means of the button on the shirt passing through the button holes 4 and 5.

The lower marginal edge of the neck band at the long end thereof is deflected upwardly as at 11, whereby the width of the neck band at the long end is gradually reduced as clearly shown in the drawings. The object of this reduction at the long end of the neck band is to have the said long end clear the button hole 10 of the neck band and the button hole 2 of the top portion 1, whereby I

am enabled to position the button holes 2 nearer the front marginal end edge of the top folded than would be otherwise possible.

The detachable button may be of any desired type.

What I claim is:—

1. A soft fold collar having a neck band and a folded over top portion, said neck band being provided with two button holes 10 at each end disposed in alinement with each other and near the lower marginal edge of the said band, said folded over top being provided with a button hole near each end disposed near its lower marginal edge and

positioned to register respectively with one 15 of the button holes in the band.

2. A collar having a neck band and a folded over top portion, the ends of the band extending beyond the ends of the top portion, and each provided with two button 20 holes substantially in alinement with each other, one of said end portions of the band being materially reduced in width whereby its lower edge will clear the innermost button hole in the opposite end of the neck band 25 when the ends are brought together.

In testimony whereof I affix my signature.
DONALD B. BECKER.
